UNITED STATES PATENT OFFICE.

WILLIAM DIETER, OF NEW YORK, N. Y., ASSIGNOR TO E. W. BLISS COMPANY, OF BROOKLYN, NEW YORK, A CORPORATION OF WEST VIRGINIA.

AUTOMOBILE TORPEDO.

1,148,155.

Specification of Letters Patent. Patented July 27, 1915.

Application filed April 3, 1915. Serial No. 18,954.

To all whom it may concern:

Be it known that I, WILLIAM DIETER, a citizen of the United States, residing in the borough of Brooklyn, county of Kings, city 5 and State of New York, have invented certain new and useful Improvements in Automobile Torpedoes, of which the following is a specification.

This invention provides an improvement 10 in automobile torpedoes whereby to cool the hydrostat forming part of the depth or immersion mechanism. The hydrostat has a diaphragm which on one side receives the water pressure and on the other side receives 15 in an air chamber the adjustable pressure of a spring. There is liability that the heat generated during the run may be sufficient to expand the air in this chamber and cause it to exert a pressure against the diaphragm 20 which adds to the pressure of the spring and opposes the hydrostatic pressure, so that it impairs the accuracy of the depth mechanism, having a tendency to cause the torpedo to run at a greater depth than that for 25 which the hydrostat was set. To prevent such heating of the air, this invention provides a construction whereby a circulation of cooling water is maintained around the spring chamber to carry away any heat and 30 prevent its reaching the air in the spring chamber.

Figure 1 of the accompanying drawings is a transverse section of a torpedo the plane of the section coinciding with the axes of 35 the springs and with the center of the diaphragm of the hydrostat; Fig. 2 is a fragmentary longitudinal section on a larger scale showing the water inlet.

Referring to the drawings, A is the shell 40 or hull of the torpedo, B is the propeller shaft or shafts, and C as a whole the hydrostat which controls the depth or immersion mechanism. This hydrostat includes a diaphragm D exposed on its lower side to a 45 water chamber E which communicates through openings a a with the exterior water, the preferred construction including a ring or annular frame b fastened to the shell of the torpedo, and a removable frame 50 c fitting within the frame b and having an annular disk portion to which the diaphragm is fastened by clamping its marginal portion between such annular part and a flange d made as part of an upright shell F 55 which incloses the spring chamber or air

chamber e. The shell F is formed with two cylindrical upright portions f f forming the spring chambers within which are inclosed the springs G G of the hydrostat, which springs react upwardly against plungers H H and press downwardly against an equalizing lever I, the middle of which has a rocking engagement at i with a disk h covering the middle portion of the diaphragm. To adjust the stress of the springs, the plungers H H are made adjustable by means of screwthreaded stems J J which are engaged by spindles j' j' having gears j j at their upper end meshing with an intervening gear k fixed on an adjusting spindle l which is accessible from the exterior and by which the adjustments of the two springs may be made simultaneously.

So far as described, the construction is that which is common in the Bliss-Leavitt 75 torpedo. The specific construction is not essential to the present invention and may be modified in accordance with any known or equivalent constructions used in practice.

The cooling means provided by the present invention will now be described. Surrounding all or any part of the spring chamber or air chamber e, is a water jacket K through which water taken from the exterior is forced to circulate. In the construction shown the jacket is not carried to the bottom of the chamber so as to inclose all of the shell F, but is confined to the individual shells f f inclosing the respective springs. The jacket is formed by surrounding each shell f with an outer shell L, so that the space between these cylindrical shells constitutes the water jacket K. Water is introduced near the top of one individual jacket through an inlet passage M, flows downwardly through the annular space surrounding one shell f, and from near the bottom thereof flows across through a passage N to the bottom portion of the other annular jacket, and ascends through the latter, passing out therefrom through an outlet passage M'. For conducting the water to the inlet M and from the outlet M', tubes P P' are provided which bridge the space between such inlet and outlet M M' and inlet and outlet openings Q Q' respectively formed through the shell of the torpedo and preferably at its upper part. Each opening Q and Q' is formed with a collar or neck q, and with a hollow screw plug r screwing 100

105

110

within the collar. The ends of the tubes P P' enter into sockets m m' beneath and n n' above, and some suitable packing material is placed in these sockets, as shown at 5 p p, to make water tight joints. It is preferable to make the tubes P P' with globular or substantially spherical end portions which form a sort of ball-and-socket joint with the respective sockets, so that even if the 10 respective sockets are not perfectly alined a tight joint will nevertheless be made.

It is an advantageous feature of the invention that in the assembling of the parts the hydrostat is first introduced and mounted 15 within the torpedo in any customary manner, and afterward the tubes P P' are inserted from above through the collars q q, after which the upper packings p p are introduced and the nuts r r are screwed down.

20 The assembling or disassembling of the parts is thus rendered very easy.

In order to force a circulation inward at the inlet side and outward at the outlet side, the inlet Q is provided with a head R which 25 bridges over the opening and is turned forward, opening on its front side as shown in Fig. 2. The outlet opening may have a similar head turned aft, although it is quite sufficient to leave it uncovered. The head R 30 is to be applied after the insertion of the tube and the screwing down of the plug. By reason of this head a sufficiently active circulation of water is maintained during all the time that the torpedo is under way.

35 This invention affords a simple and easily applied construction whereby to effectively cool the spring chamber and prevent the heating of the air therein, and hence has the effect of avoiding any abnormal action 40 of the depth mechanism due to the pressure of such heated air against the diaphragm.

The invention is not limited to the precise construction shown, being subject to a reasonable range of equivalents such as are 45 within the perception of those skilled in this art.

I claim as my invention:—

1. In a torpedo, a hydrostat having a water jacket around its spring chamber, 50 tubes connecting from the inlet and outlet of such water jacket to inlet and outlet openings in the torpedo shell, and a head applied to one of said openings to force a circulation through said tubes.

55 2. In a torpedo, a hydrostat having a water jacket around its spring chamber,

said jacket formed with inlet and outlet openings, the torpedo shell formed with inlet and outlet openings, and removable tubes connecting between said inlet openings and 60 between said outlet openings respectively.

3. In a torpedo, a hydrostat having a water jacket around its spring chamber, said jacket formed with socketed inlet and outlet openings, the torpedo shell formed with inlet and outlet collars forming sockets, and removable tubes bridging between the inlet 65 openings and outlet openings respectively, the end portions of said tubes fitting in the respective sockets, and means for packing 70 said sockets to avoid leakage.

4. In a torpedo, a hydrostat having a water jacket around its spring chamber, said jacket formed with socketed inlet and outlet 75 openings, the torpedo shell formed with inlet and outlet collars forming sockets, and removable tubes bridging between the inlet openings and outlet openings respectively, said tubes insertible through said collars, and perforated means for closing the openings in said collars after the insertion of 80 said tubes.

5. In a torpedo, a hydrostat having a water jacket around its spring chamber, said jacket formed with socketed inlet and outlet 85 openings, the torpedo shell formed with inlet and outlet collars forming sockets, and removable tubes bridging between the inlet openings and outlet openings respectively, said tubes insertible through said collars, 90 and annular screw plugs screwing into said collars against said tubes.

6. In a torpedo, a hydrostat having a water jacket around its spring chamber, said jacket formed with socketed inlet and outlet 95 openings, the torpedo shell formed with inlet and outlet collars forming sockets, and removable tubes bridging between the inlet openings and outlet openings respectively, the end portions of said tubes formed as 100 balls fitting in the respective sockets, whereby the tubes adapt themselves to any want of alinement of the sockets, and fastening means for holding said tubes in place.

In witness whereof, I have hereunto 105 signed my name in the presence of two subscribing witnesses.

WILLIAM DIETER.
